UNITED STATES PATENT OFFICE.

LOUIS R. ALBERGER, OF NEW YORK, N. Y., ASSIGNOR TO ALBERGER
CONDENSER COMPANY, OF NEW YORK, N. Y., A CORPORATION OF
NEW YORK.

JET-CONDENSER.

SPECIFICATION forming part of Letters Patent No. 723,972, dated March 31, 1903.

Application filed February 24, 1902. Serial No. 95,176. (No model.)

To all whom it may concern:

Be it known that I, LOUIS R. ALBERGER, a citizen of the United States of America, and a resident of the city, county, and State of New York, have invented certain new and useful Improvements in Jet-Condensers, of which the following is a specification.

My invention relates to means for effecting the condensation of steam and other vapors, and it has special reference to that class or type of jet-condensers arranged in an elevated position and having separate water and dry-vacuum pumps, the one handling only the water for condensation, which it discharges into the condenser, while the other performs the duty of exhausting the air from the condenser and the pipe system, said type of condenser having also a barometric tail-pipe or stand-pipe, through which the condensed steam and heated water fall by gravity against the pressure of the atmosphere and escape from the apparatus, or having a pumping apparatus to remove said water or liquid.

The object of the invention is to provide an improved condenser of this type in which may be combined the various advantageous features of the parallel-current and of the counter-current condenser; and the invention consists, essentially, in the novel and useful construction, arrangement, and combination of parts and in numerous details and peculiarities thereof, substantially as will be hereinafter described and then more particularly pointed out in the ensuing claims.

In the accompanying drawings, illustrating my invention, Figure 1 is a side elevation of my present improved jet-condenser shown in connection with the pumps and the pipe system. Fig. 2 is an enlarged vertical section of the condenser-chamber with the interior and the connected parts. Fig. 3 is a detail sectional view of the automatically-adjustable spraying-cone belonging to the inlet-nozzle for the injection-water, the same being shown on a larger scale than it is in Fig. 2. Fig. 4 is a horizontal transverse section on the line $x-x$ of Fig. 2. Fig. 5 is another horizontal transverse section on the line $y-y$ of Fig. 2.

Similar characters of reference denote cor-

responding parts throughout the different figures of the drawings.

1 denotes the shell of the condensing-chamber, being of a general cylindrical form and having any desired dimensions. At the lower end of the main shell 1 is the conical shell 2, which connects with the tail-pipe or barometric tube 3, having its lower end submerged in the hot-well 4. At the top of the main shell 1 is a shell or casing 26, within which are an air-cooler and a separating-chamber. At some suitable point in the wall of the shell 1 is an opening 11 for the admission of exhaust-steam into the condenser from the engine or other apparatus with which the condenser may be connected.

12 designates the exhaust-steam pipe that leads from the engine and is connected to the condenser at the opening 11, as shown in Fig. 1. At another point in the wall of the shell 1, preferably opposite to the exhaust-inlet 11, is an injection-water inlet 6, that is entered by the water-supply pipe 7, running from the water-pump 8 or other water-supply, whereby water is transferred to the condenser to be used for purposes of condensation. The water reaching the condenser through pipe 7 and inlet 6 enters the lateral horizontal branch pipe 27 and the inner chamber or elbow 18, by which its course is deflected to a downward direction. Chamber 18, which may be called a "spray-chamber," has a bottom outlet 28, through which the water will issue into the interior of the condenser and strike the exterior surface of the hollow spraying-cone 16. Both the opening 28 and the spraying-cone 16 are preferably provided, respectively, with a similar series of peripheral teeth 29 and 30 for converting the issuing water into spray, breaking it up into small particles, or finely subdividing it, so that as much surface as possible may be exposed for contact with the steam. The spray-chamber 18 and the spray-cone 16 may be considered together as a spraying-nozzle for discharging the injection-water into the condenser. Cone 16 is attached to and carried by the lower end of a vertical pipe 17, which is yieldingly supported in a stationary central tubular bearing 25, within which it is telescopically arranged, so as to be susceptible of vertical adjustment,

100

which adjustment is accomplished automatically. In describing the yielding support for said pipe 17 and the means whereby its adjustment is automatically regulated I first 5 mention a rod 19, securely fastened at its upper end to some part of the top structure of the condenser—as, for instance, to some part of the air-cooler—and extending downwardly into the upper end of the pipe 17. The lower 10 end of rod 19 is screw-threaded and provided with a jam-nut 44. (See Fig. 3.) On the rod, above the jam-nut 44, is a skeleton frame comprising a ring 22, equal in diameter to the pipe 17 and fitting loosely therein, integral 15 with which ring 22 is a series of diagonal arms 23, that are likewise integral with a small ring 24, that loosely surrounds the rod 19 just above nut 44. Screwed into the upper end of pipe 17 is a ring 21, that forms an inner rab- 20 bet or shoulder at that point. Between ring 21 and ring 22 is tensioned a spiral spring 20. It will be obvious that any agency acting to draw the pipe 17 downward will, if the rod 19 be held stationary, as stated, serve to 25 compress spring 20, the degree of compression being proportionate to the strength of the downward pull, and when such strength decreases spring 20 will expand to a greater or less extent and in so doing will act against 30 the ring 22 and lift pipe 17 to its former position. In other words, I have here provided means for yieldingly or elastically supporting the pipe 17 and also the spraying-cone 16. I have already stated that the cold water en- 35 tering the condenser issues into the interior chamber through the opening 28 and between said opening and the cone 16, which latter in consequence of its funnel form spreads the issuing water into an umbrella-shaped sheet, 40 which on account of the comb-teeth 29 and 30 is broken into a shower of spray. In practical operation the volume of water passing from the supply-pipe into the condenser through this nozzle will vary at different 45 times, according to the temperature of the water and the quantity of steam to be condensed, and it is important that the spraying of the water be effectively performed under these varying conditions. This I accomplish 50 by causing the spray-cone 16 to change its position so as to maintain practically a constant pressure of the water at the nozzle irrespective of the volume of water passing. Such movement of cone 16 in correspondence 55 with the variation of the volume of the water is provided for through the yielding means by which the cone is supported, as I have above described. Therefore the size of the opening in the nozzle for the delivery of wa- 60 ter into the interior chamber is automatically enlarged or decreased in proportion to the volume of the water supplied. Adverting again to the rod 19, it will be observed that its upper end 42 is screw-threaded and pro- 65 vided with a jam-nut 41, and in the present example of the invention this end 42 passes through a plate 33 in the air-cooler and the

nut 41 rests on the upper face of said plate. Of course the spring device which I have shown and described for the purpose of yieldingly supporting the spraying-cone is only one of many ways for carrying said cone. 70

In lieu of the springs, weights or balancing-pistons or other instrumentalities may be employed to yieldingly sustain the spraying-cone and air-pipe, and I reserve the liberty, 75 therefore, of utilizing any desired means that will serve the purpose.

Within the shell 1 is an inner cylinder or barrel 13, open at the top and bottom and arranged concentrically with the shell 1, so as to leave an annular space 45 between shell 1 and cylinder 13, the upper end of which annular space is contiguous on one side to the steam-inlet 11. This inner cylinder 13 is supported by brackets 15 on shell 1 or by other suitable means, and its bottom periphery is preferably provided with a series of slots 14 to provide spraying comb-teeth similar to those of cone 16, the object of this comb being to allow some of the water that falls in a deluge through the cylinder 13 to spread laterally between the teeth into the lower end of annular space 45. Thus it will be understood that the exhaust-steam that enters the 95 condenser through the inlet 11 will part of it pass into the cylinder 13, while another portion will enter the annular space 45. The part that enters the cylinder 13 will of course directly meet the water that is showering from the central nozzle, while the part which flows into the annular chamber 45 will not come into contact with the water until it reaches the lower end of said chamber, and the water with which it does then come into contact will have become 100 more or less heated by its previous action on steam in cylinder 13. Arranged centrally in the shell 26, at the top of the condenser, is an air-cooling structure consisting of a cylinder 31, having its lower edge cleft, slotted, or otherwise fashioned to provide openings 43, through which water can flow, as well as to furnish feet for the support of the cylinder, which feet rest on the top plate 46 of main shell 1, which plate is a shallow water-tight 110 receptacle. (See Fig. 2.) Said cylinder 31 reaches from the bottom to the top of shell 26. It contains a series of two or more horizontal partitions or plates 33, provided with openings 34, having serrated edges 35 to break 115 up the water that comes in contact with them and allow it to present a large surface to the air. The openings 34 in the alternating partitions are so arranged at opposite sides of the center of the partitions as to cause the 120 falling water to pursue a circuitous direction or back-and-forth movement as it courses through the cooler. A pipe 9 runs from the pipe 7 to the shell 26 and couples to a short connecting-pipe 10, which leads to the upper 125 part of the cooler-cylinder 31, and through these pipes 9 and 10 cold injection-water is supplied to the air-cooler. This water falls over plates 33, arranged in the cylinder 31, 130

until it reaches the bottom of the latter and passes through the openings 43 into the bottom of an annular separating-chamber 32, surrounding cooler-cylinder 31, from which 5 chamber 32 its exit is made by way of a vertical pipe 40, that leads downward through the condenser to the lower conical shell 2 or to a point from which the water can easily fall into said shell. The cylinder 31 is provided 10 near its upper end with an opening 37, through which air and any entrained particles of water pass over into the separating-chamber 32. This latter chamber is provided with an air-outlet opening 36, to which is 15 connected the air-pipe 38, that leads to the dry-vacuum pump 39, the operation of which pump exhausts air from the condenser and creates and maintains as perfect a vacuum as possible. Any air that becomes separated 20 from the injection-water below the main delivery-nozzle of the latter within the condensing-chamber will pass upward through pipe 17 into the air-cooler and there come in contact with the cold injection-water entering 25 through pipe 9, and when this air reaches the top of the cooler it will, as I have already stated, pass into the separating-chamber 32, where any entrained particles of water will be separated from the air, and the air will be 30 withdrawn from the chamber 32 through the outlet 36, while the water will pass away through pipe 40.

The operation may be briefly described, as follows: Exhaust-steam enters the condenser 35 through inlet 11 and impinges directly upon the cold water that is being delivered in a shower of spray from the central nozzle, which causes a portion of steam to be driven downward and against the inner wall of the inner 40 cylinder 13, while another portion of exhaust-steam that has not yet come in contact with water passes down into the annular space 45. The water which meets the steam in the inner cylinder 13 will of course be partially heated thereby. The steam in the annular space 45 when it reaches the lower end 45 thereof will meet this partially-heated water and will be condensed to the extent that the temperature of the water will permit. Thus 50 the heated water enters the cone 2 at the highest practical temperature. Air and uncondensable vapors that are entrapped by the water will be drawn into the cone 2. The velocity of the passage of the water through the 55 cone 2 will increase as the diameter of the cone contracts toward its bottom, and hence the air and vapors will be carried down into the tail-pipe 3 and out into the atmosphere, not being allowed an opportunity to separate from 60 the water. Air that is not so entrapped will after having passed through the cold water that flows in a circle around and close to the spraying-cone 16 enter the space under said cone and escape upward through pipe 17 and 65 then through the air-cooler 31 into the separating-chamber 32, where, as the velocity of travel is greatly reduced, any particles of wa-

ter will fall out of the air before it passes to the vacuum-pump through the air-outlet 36, and this water will find its way to the condensing-chamber through pipe 40, while at the same time water which has been carried into the air-cooler from the pipe 9 will flow into the bottom of the separating-chamber 32 through the opening 43 and similarly pass 75 thence into the condensing-chamber through pipe 40, this additional water supplied to the condensing-chamber from the air-cooler being employed therein to condense the steam in the same manner as the great bulk of the 80 injection-water that enters through the spraying-nozzle. By this design and arrangement of parts the partly-heated water contacts with incoming steam before leaving the condenser, and the air is cooled by cold injection-water 85 before going to the air-pump, and the best transfer of heat is obtained without stopping the flow of water. An excess of steam due to a sudden overload on the engines will tend to further drive the water down into the cone 90 and tail-pipe, the vacuum falling of course to a degree corresponding with the increased temperature of the water leaving the condenser. This fall of vacuum, however, does not disarrange the action of the condenser. 95 The direction of the flow of the fluids is unchanged. Hence the characteristic excellencies of both a parallel-current and counter-current condenser are secured by this construction, for not only does hot water come in 100 contact with incoming hot steam and air come in contact with incoming cold water, two of the advantages which are paramount in a counter-current condenser, but also the action of the incoming steam increases the speed of 105 the flow of the water and obviates the possibility of flooding the vacuum-pump, the high speed of the liquid acts to carry off a large amount of the air, so that a quite complete vacuum is possible without any vacuum- 110 pump, and the surface of the spraying-water in contact with the steam is submerged before the water can enter the exhaust-pipe, which are some of the advantages belonging ordinarily to a parallel-current condenser. 115

Manifestly the precise construction and combination set forth herein and illustrated in the drawings are intended simply to exhibit one example of the invention or one form in which it may be embodied, and I do 120 not intend to be restricted closely thereto, but reserve the liberty of varying, changing, and rearranging the parts as experience may advise or suggest in order that the best practical form of the invention may be had. 125

Having thus described my invention, what I claim as new, and desire to secure by Letters Patent, is

1. In a condenser, the combination with a condensing-chamber having an exhaust-inlet 130 and also a water-inlet, of a spraying or spreading device for the water, and means for yieldingly hanging the same, all arranged so that the downward discharge of water against the

spraying device may adjust the latter to allow the inflow of a greater or less amount of water.

2. In a condenser, the combination with a condensing-chamber having an exhaust-inlet and also a water-inlet, of a spraying or spreading device for the water and a pipe to which said device is attached, which pipe provides for the escape of air.

10. 3. In a condenser, the combination with a condensing-chamber having an exhaust-inlet and also a water-inlet, of a yielding spraying device for the water, and an air-cooler to which air is conducted from beneath said device.

15. 4. In a condenser, the combination with a condensing-chamber having an exhaust-inlet and also a water-inlet, of a yielding spraying device for the water, an air-cooler wherein the air is brought into contact with cold injection-water, and means for conducting air to the air-cooler from beneath the spraying device.

20. 5. In a condenser, the combination with a condensing-chamber having an exhaust-inlet and also a water-inlet, of a spraying or spreading device for the water, a pipe to which said device is attached and means for yieldingly supporting said pipe.

25. 6. In a condenser, the combination with a condensing-chamber having an exhaust-inlet and also a water-inlet, of a spraying or spreading device for the water, a pipe by which said device is supported, and an air-cooler entered by the other end of said pipe so that air from below the spreading device may be conveyed directly to the cooler.

30. 7. In a condenser, the combination with a condensing-chamber having an exhaust-inlet and also a water-inlet, of a spraying or spreading device for the water, a pipe by which said device is carried, yielding means consisting essentially of a spring for supporting said pipe, and an air-cooler entered by said pipe.

35. 8. In a condenser, the combination with a condensing-chamber having an exhaust-inlet and also a water-inlet, of a spraying or spreading device for the water, a spraying-chamber in connection with which it is arranged, and means for yieldingly hanging the device so that the volume of the water passing downwardly by said device may automatically regulate the size of the opening.

40. 9. In a condenser, the combination with a condensing-chamber having an exhaust-inlet and also a water-inlet, of a spreading or spraying device for the water, a pipe to which it is attached, an air-cooler entered by said pipe, and means for delivering cold injection-water to said cooler together with means for exhausting the air from the cooler.

45. 10. In a condenser, the combination with a condensing-chamber having an exhaust-inlet and also a water-inlet, of a spraying device for the water, an air-pipe by which said device is supported, an air-cooler entered by said pipe, means for delivering water to said cooler, a chamber wherein air and water may

be separated, a pipe for carrying water from said chamber and vacuum-producing means for exhausting air from said chamber.

50. 11. In a condenser, the combination with a condensing-chamber having an exhaust-inlet and also a water-inlet, of means for spreading or distributing the water in said chamber, a centrally-arranged pipe for conducting air from below said means, an air-cooler entered by said pipe, which cooler contains perforated plates and is provided with water-discharge openings at the bottom, means for delivering water to the top of the cooler, a chamber surrounding the cooler wherein air and water are separated, a pipe for conveying away said water and means for exhausting the air from the separating-chamber.

55. 12. In a condenser, the combination with a condensing-chamber having an exhaust-inlet and also a water-inlet, of a tail-pipe, a shell between the tail-pipe and condensing-chamber, and a concentric cylinder within the condensing-chamber for providing an annular chamber to receive a portion of the exhaust, and means for spraying the injection-water in the inner cylinder.

60. 13. In a condenser, the combination with a condensing-chamber of an inner cylinder within the condensing-chamber for providing an annular chamber to convey a portion of the exhaust to the lower end where it is discharged.

65. 14. In a condenser, the combination with a condensing-chamber having an exhaust-inlet and also a water-inlet, of a concentric cylinder within the condensing-chamber for providing an annular chamber to convey a portion of the exhaust through it to the lower end where it is discharged, and means for spraying the water in the condensing-chamber.

70. 15. In a condenser, the combination with a condensing-chamber having an exhaust-inlet and also a water-inlet, of an inner cylinder concentric with the condensing-chamber to provide an annular chamber for receiving a portion of the exhaust, means for distributing the spraying-water within the inner cylinder so that partially-heated water may be brought into contact with the steam that courses through the annular chamber.

75. 16. In a condenser, the combination with a condensing-chamber, of an inner spray-chamber that receives the injection-water, a spraying-cone beneath said spray-chamber, a pipe for supporting said cone, and means consisting essentially of a spring for yieldingly supporting the pipe, all arranged so that the discharge of water from the spray-chamber against the cone may adjust the latter to allow the exit of a greater or less amount of water.

80. 17. In a condensing system in which the air or a part of the air is removed from the condensing-chamber by an air-pump, the combination with the condenser and connections to the air-pump, of a yielding spraying device

for the water, and an air-cooler for cooling the air on its way to the air-pump from a point beneath the spraying device, in which cooler the air is brought into contact with water.

18. In a condensing system in which the air or a part of the air is removed from the condensing-chamber by an air-pump, the combination with the condenser and connections to the air-pump, of a spraying device for the water, and an air-cooler for cooling the air on its way to the air-pump from a point beneath the spraying device, in which cooler the air is brought into contact with a separate supply of water.

19. In a condensing system in which air or a part of the air is removed from the condensing-chamber by an air-pump, the combination with the condenser and connections to the air-pump, a tail-pipe and a conical shell between the tail-pipe and condensing-chamber, of an inner cylinder within the condensing-chamber for providing an annular chamber for receiving a portion of the exhaust and conveying it to the lower end where it is discharged, means for spraying the injection-water in the condensing-chamber, and an air-cooler in which the air removed from beneath the spraying device is brought into contact with the cooling liquid.

20. In a condenser, the combination with a condensing-chamber having an exhaust-inlet and also a water-inlet, of a spraying or spreading device for the water entering said chamber, and an air-cooler having a supply of water separate from the condensing-chamber supply. 35

21. In a condenser, the combination with a condensing-chamber having an exhaust-inlet and also a water-inlet, of a spraying or spreading device for the water entering said chamber, means for yieldingly supporting said device, and an air-cooler having a supply of water separate from the condensing-chamber supply. 40

22. In a condenser, the combination with a condensing-chamber having an exhaust-inlet and also a water-inlet, of a spraying device for the water, a pipe to which said device is attached, an air-cooler to which air is conducted through the pipe from beneath said spraying device, said air-cooler having a water-supply separate from the condensing-chamber supply. 45
